UNITED STATES PATENT OFFICE.

ANDREW HOWARD, OF WILKINSBURG, PENNSYLVANIA.

DESIGN FOR A CHIMNEY.

SPECIFICATION forming part of Design No. 28,845, dated June 14, 1898.

Application filed December 22, 1897. Serial No. 663,108. Term of patent 14 years.

To all whom it may concern:

Be it known that I, ANDREW HOWARD, a citizen of the United States, residing at Wilkinsburg, in the county of Allegheny and State of Pennsylvania, have invented a certain new Design for a Chimney for Incandescent Gas-Lights; and I do hereby declare the following to be a full, clear, and exact description of the invention, such as will enable others skilled in the art to which it appertains to make and use the same.

My design has relation to glass chimneys.

The accompanying drawing is a side view of a chimney, showing my new design.

The chimney consists of the cylindrical part

A and the smaller cylindrical part E. A rounded shoulder B is formed at the upper end of the part A, and this is surmounted by another rounded shoulder D, these two shoulders merging into the parts A and E. 20

Having described my invention, I claim as new and desire to secure by Letters Patent—

The design for a chimney herein shown and described.

In testimony whereof I affix my signature 25 in presence of two witnesses.

ANDREW HOWARD.

Witnesses:

B. P. HOWARD,
JOSEPHINE II. STEWART.
